ANDREW J. ALLARD, OF RICHMOND, VIRGINIA, ASSIGNOR OF ONE-THIRD TO T. F. GREEN AND ONE-THIRD TO DAVID R. CREECY, JR., OF RICHMOND, VIRGINIA.

ELECTRIC TRAIN SIGNALING AND CONTROLLING MEANS.

1,060,400.

Specification of Letters Patent. Patented Apr. 29, 1913.

Application filed October 4, 1910, Serial No. 585,296. Renewed January 28, 1913. Serial No. 744,782.

To all whom it may concern:

Be it known that I, ANDREW J. ALLARD, of Richmond, in the county of Henrico and State of Virginia, have invented certain new and useful Improvements in Electric Train Signaling and Controlling Means; and I do hereby declare the following to be a full, clear, and exact description of the invention, such as will enable others skilled in the art to which it appertains to make and use the same.

This invention relates to improvements in electric train-signaling and controlling means, the object of my present invention being to provide simple and efficient means which shall be operative automatically to actuate a signal on the locomotive and, if said signal be ignored, to automatically stop the train before it reaches an open switch.

A further object is to provide means whereby the engineer can, upon arriving in proximity to the switch or siding, communicate with a despatcher's office.

With these objects in view, the invention consists in certain novel features of construction and combination of parts as hereinafter set forth and pointed out in the claims.

In the accompanying drawings, Figure 1 is a diagrammatic view showing the arrangement of circuits and devices adjacent to a railroad siding. Fig. 2 is a diagrammatical view showing the circuits and devices on a locomotive. Fig. 3 is a detail view of the brake controlling devices, and Fig. 4 is a detail view of one pair of relays.

1, 1, represent the rails of a road and 2 a siding; at each end of which latter pivoted switch points 3 are located.

Some distance rearwardly of the switches of the siding, contact rails 4 (each preferably about one-thousand feet in length), are located between the track rails; and between the contact rails 4 and the switches, shorter contact rails 5 are located between the track rails,—said contact rails being adapted to coöperate with a contact shoe on each locomotive as hereinafter explained.

In advance of the switches at respective ends of the siding pairs of relays 8—9 are located and in order that the armatures of said relays shall respond to currents of different voltages under different conditions, the springs 10 connected with said arma-

tures will be so adjusted that the armature 55 of each relay 8 will be actuated upon the passage of a low voltage current through its coils, and so that the armature of each relay 9 will be actuated only when a current of higher voltage passes through its coils. For 60 convenience, the relays 8 will be hereinafter referred to as low voltage relays and the relays 9 will be designated as high voltage relays.

The coils of the relays are included in 65 series with each other and a line wire 11 connects one terminal of the relay magnets at one end of the siding with one terminal of the relay magnets at the other end of the siding. The other terminal of each pair 70 of relay magnets is connected with a battery 12 and the latter is connected, by a conductor 13, with one terminal of a battery 14. The other terminal of each battery 14 is connected with the contact point 15 of a 75 circuit closer, the casing 6 of which is electrically connected with one of the track rails in proximity to a pivoted switch point 3 of the siding. A spring actuated rod 7 is mounted in and electrically associated with 80 the casing of each circuit closer and provided at one end with a head 7^a to coöperate with the contact point 15. One end of the rod 7 of each circuit closer bears against an adjacent switch point 3 and the pressure 85 of the latter against said rod maintains the head 7^a normally out of contact with the contact point 15, when the siding switch is open. The casing 6 of each circuit closer is connected, by means of a conductor 16, with 90 one terminal of a resistance 17 and the other terminal of this resistance is connected, by means of a conductor 17^a with the conductor 13 at a point between the batteries 12 and 14. It will thus be seen that the relay magnets 95 at both ends of the siding are included in series in a constantly closed circuit comprising the line wire 11, a track rail, the batteries 12 and the resistances 17, and that, by reason of the resistances 17, the voltage 100 of the current in this circuit is such that the low-voltage relay magnets only will be sufficiently energized to actuate their armatures, and hence the local circuits (hereinafter described) controlled by the 105 relays 8 will be open as shown in Fig. 1 of the drawing.

At each end of the siding, the armature

levers of the relays are connected, by means of a conductor 18, with a track rail. The contact 19 of the relay 8 is connected by a conductor 20 with one terminal of a battery 21 and the other terminal of this battery is connected by a conductor 22 with a conductor 23. One end of the conductor 23 is connected with short contact rail 5 and the other end is connected with one terminal 10 of a resistance 24, the other terminal of said resistance being connected with a switch contact 25 with which the arm 26 of a switch 26^a coöperates. This switch arm is connected by means of a conductor 27 with a long contact rail 4. The contact 28 for the armature lever of each relay 9, is connected, by a conductor 29 with the conductor 20. The switch 26^a comprises two mechanically connected arms 26 and 30, and 15 suitable contacts for said arms.

It will, of course, be understood that the construction and arrangement of circuits and devices at both ends of the siding will be the same as above described, and their 20 operation will, hereinafter, be made apparent.

Each locomotive is provided with a contact shoe 35 to engage the contact rails 4, and 5, and in the cab of the locomotive, a 30 solenoid 36 is located, the core of this solenoid being connected with a semaphore 37 also located in the cab. A switch 38 is also located in the cab and comprises a longitudinally movable bar provided with a plurality of contact plates 39, 40, 41 and 42, and a plurality of contact arms 43, 44, 45, 46, 47, 48 and 49. The switch arms 43, 49 are normally connected by the contact plate 39, and the arm 49 is connected by conductors 35 40 50—51 with the contact shoe 35. The switch arm 43 is connected by a conductor 52 with one terminal of the coil of solenoid 30, the other terminal of said coil being connected, by means of a conductor 53 with the truck frame.

When a car or locomotive approaches one end or the other of the siding and the siding switch is closed, no signal will be received in the cab of the locomotive. When the 50 siding switch is opened, the rod of the circuit closer will be moved by its spring and the head 7^a will engage the contact point 15, thus closing the circuit of battery 14 and placing resistance 17 in shunt around this battery. Batteries 12 and 14 will now be in series with each other and sufficient current will be supplied to energize the high voltage relay 9 and cause the armature of the latter to engage the contact point 28. 55 The local circuits of battery 21 will now be closed at the relay 9, but as this circuit includes a track rail and contact rails, it will remain open until a train approaches the siding and the contact shoe on the locomotive engages one of said contact rails.

Assume now, that the siding switch is open and that a locomotive has reached the long contact rail 4 so that the shoe 35 on the locomotive engages said contact rail: Under such conditions, a circuit will be established including battery 21, resistance 24, contact shoe and truck frame of the locomotive, and the circuits on the latter which includes the semaphore solenoid. The semaphore in the cab will thus be actuated and moved to "danger" or "stop" position, indicating to the engineer that the switch at the siding is open. Should the engineer disregard such warning, his train will be automatically stopped, by means of appliances and in the manner which will now be explained.

A cylinder 54 (shown in detail in Fig. 3) is located on the locomotive and provided with a piston 55, the rod 56 of which is connected with the air-brake valve mechanism 85 (not shown) for operating the same. The cylinder 54 is provided with a valve chamber 57 which communicates with the respective ends of the cylinder by means of ducts 58—59, and said valve casing is also 90 provided with exhaust ports 60. An air supply pipe 60^a communicates with the valve chamber between the exhaust ports. A reciprocating valve 61 is located within the valve chamber 57 and provided with suitable ducts for connecting respective ends of the cylinder with the air supply pipe and an exhaust port, alternately so as to cause reciprocation of the piston 55 for operating the valve controlling mechanism of the air brakes. A hand lever 62 is pivoted at one end to a suitable support 63 and this lever is connected, by means of a rod 64 with the valve 61, said lever being movable in one direction by a spring 65. The valve 61 is 105 maintained normally in the position shown in Fig. 3, by means of a latch 66 pivoted at one end to a fixed support and adapted at its other end to engage a lug or hook 67 on the lever 62, such engagement being normally maintained by means of a spring 68. The latch lever 66 is provided with an armature 69 for an electro-magnet 70, and this magnet is controlled by devices presently explained, to actuate the latch lever and release the hand lever 62. When the hand lever shall have been thus released, the spring 65 will be free to shift the valves 61 and thus admit air behind the piston 55 to operate the valve mechanism of the brakes.

The brake controlling devices above described will be located in such position under the locomotive that it will be necessary for the engineer to leave his cab before he can reach them for resetting, such resetting being accomplished by operating the hand lever 62 until its latch devices 66—67 become engaged.

The coil of the magnet 70 is included in a normally open local circuit with a battery 130

71 and a switch 72,—this circuit being traced on Fig. 2 as follows:—The battery 71 is connected by a conductor 73 with one terminal of the coil of magnet 70 and the other terminal of said coil is connected, by a conductor 74, with the switch lever 72. This switch lever is intended to coöperate with a fixed contact 75 and the latter is connected, by a conductor 76, with the battery 71. This circuit is maintained normally open by the engagement of a pivoted latch 77 with the switch lever 72 as shown in Fig. 2, and when said switch lever has been released by the operation of the latch lever, it will be thrown, by the action of a spring 78, and be permitted to coöperate with the contact 75 to close said local circuit. The switch devices above described for controlling the local circuit of magnet 70, will also be located under the locomotive, so as to necessitate the engineer leaving the cab to reset them. It is apparent that the engineer cannot reset the brake controlling devices shown in Fig. 3, until he has first reset the switch 72 to open the local circuit including the magnet 70 because the latter would not permit the operation of the latch lever 66 as long as the magnet 70 remains energized. The latch 77 is maintained normally in engagement with the switch lever 72 by means of a suitable spring and the operation of said latch is controlled by an electro-magnet 79. One terminal of the coil of this magnet is connected, by a conductor 80, with the conductor 51, the latter being connected with the contact shoe 35 as before explained. The other terminal of the coil of magnet 79 is connected with one end of a stationary resistance 81, the other end of said resistance being connected with the movable arm 82 of a speedometer 83 of any preferred construction and suitably connected with the car axles or wheels. The arm 82 of the speedometer also forms a switch arm adapted to coöperate with a contact 84, the latter being connected, by means of a conductor 85, with the conductor 53. The speedometer will be so set that the circuit including the magnet 79 will be closed at 82—84 when the train is running beyond a predetermined rate of speed,—preferably, five miles per hour or more.

The speed of the train when it reaches the long contact rail and while it is passing over such rail would (in most instances) be such that the circuit controlled by the speedometer would be closed, but the voltage of the current supplied by the batteries 21 would be so cut down by the resistances 24 and 81, that the magnet 79 would not be sufficiently energized to operate the trip 77, and hence the circuit of the magnet 70 which controls the brake mechanism, would be kept open.

As before explained, the semaphore 37 in

the cab will be moved to "danger" or "stop" position, when the shoe 35 is in engagement with the long contact rail 4. At the forward end of this long contact rail, a post 86 will be located alongside the railroad to indicate to the engineer, the end of the long contact rail, and therefore, the necessity for slackening the speed of the train or stopping it if the semaphore 37 still remains at "danger." Should the engineer disregard the warning of his semaphore and permit the train to continue at a rate of five miles per hour (more or less, according to the setting of the speedometer) and the shoe 35 should reach the short contact rail 5, the air brakes on the train would be at once applied, by reason of the automatic manipulation and operation of circuits and devices, as follows: When the shoe 35 leaves the long contact rail 4 and engages the short contact rail 5, those portions of the circuit which include the resistance 24 will be opened and the circuits of the battery 21 will be closed through the conductor 23, short contact rail 5 and the cab circuits, thus placing the full voltage supplied by the battery 21 in the short contact rail and cab circuits. The circuit of the magnet 79 being now closed at the speedometer, and the resistance 24 having been cut out, sufficient current will be supplied by the battery 21 to so energize the magnet 79 as to cause it to actuate the trip 77 and release the switch lever 72. This switch lever will then be promptly moved by the spring 78, into engagement with the contact 75 and close the local circuit including the magnet 70 and battery 71. The magnet 70 will then move the trip 66 and release the lever 62, whereupon the action of the spring 65 will shift the valve 61 and permit a movement of the piston 55 to operate the valve mechanism of the air brakes and the consequent application of the latter, thus automatically stopping the train. Before the train can proceed, the engineer must alight from his cab and manually reset, first the switch lever 72 and then the lever 62 as previously explained. Should the siding be now closed, the movement of the switch point will move the head 7^a of the circuit closer away from the contact point 15 and the circuit of battery 14 will be opened, but the circuit of the relays will remain closed through the battery 12 and resistance 17 in series. The voltage in the relay circuit having now been reduced by the removal of the battery 14 and including of the resistance 17 in series with the battery 12 and relay magnets, the armature of the high voltage relay 9 will be released and the local circuit which includes the battery 21 will be opened, thus open-circuiting the signal controlling devices in the cab of the locomotive if the latter be in such position that its shoe 35 is in engagement with one of the contact rails.

The semaphore would then move to "safety" and indicate to the engineer that the siding switch has been properly reset.

Should it be desired that the train shall 5 enter the siding, this may be accomplished without causing the automatic operation of the brakes if the engineer will run his train past the contact rail 5 at a rate of speed less than five miles per hour, because the speedometer would not permit the closing of the brake controlling circuits unless the train is 10 running at the rate of five miles per hour or other predetermined rate of speed at which the speedometer might be set.

15 Should the circuit embracing the line conductor 11 track rail, relays, resistance 17 and circuit closers become impaired, as by a breaking or grounding the low voltage relays 8 would at once become deenergized so 20 that their armatures would be released and be permitted to engage the contacts 19 of the local circuits. Under such conditions, a train approaching the siding from either end would (upon reaching a long contact rail 4) 25 receive a "danger" or "stop" signal, because such local circuit would be closed through the semaphore circuit on the train. When such a condition exists, it is desirable (in order to avoid holding the train an indefinite length of time) that the engineer 30 shall be enabled to report to a despatcher's office and receive orders. For this reason, a telephone 90 is provided in the cab, and the arms 26-30 of the switch 26^a are adapted 35 (when thrown from the position shown in Fig. 1) to engage contacts 87, with which conductors 88 leading to telephone line wires, are connected. In the cab, one terminal of the battery 71 is connected with a 40 telephone terminal by means of conductors 76-91, and the other terminal of said battery is connected with switch arm 48, by means of conductors 78-92, and the switch arm 48 is electrically connected with switch 45 contact 40 by a conductor 93. The switch arm 94 of the telephone is connected by conductor 95 with arm 46 of the switch 38, and the contact point 96 for the telephone switch arm 94, is connected, by a conductor 97 with 50 the arm 44 of switch 38. The contact point 98 is connected in the talking circuit of the telephone and the conductor 91 is connected with the arm 45 of switch 38. The contact 41 of the switch 38 is connected by a conductor 100, with the truck frame. The switch 38 is maintained in its normal position by means of a spring 99.

When the engineer desires to communicate with the despatcher's office, he will first 60 throw the switch 26^a to connect the telephone line wires (through the medium of conductors 24 and 101) with a track rail 3 and a conductor rail 4 and he will then move the switch bar 38 longitudinally. The 65 result of this will be to include the battery

71 in circuit with the telephone line and in circuit with a rheotome bell (not shown) at the despatcher's office. As soon as the engineer removes the telephone receiver from its hook, the calling battery 71 will be cut out 70 and the talking circuit of the telephone will be closed. The engineer can now receive orders from the despatcher and if such orders be for him to proceed, the engineer will first restore the switches 26^a and 38 and then proceed with his train at a rate less than five miles an hour (more or less according to the setting of the speedometer 82) until he has 75 passed the short conductor rail 5.

Having fully described my invention what 80 I claim as new and desire to secure by Letters-Patent, is:-

1. The combination with a railway block including siding switches, rolling equipment, and signaling means on the rolling equipment, of high and low voltage relays 85 at each end of the block, a closed electric circuit including the relays at both ends of the block, resistances included in said closed circuit, normally open shunt circuits around 90 said resistances, circuit closers in said shunt circuits and disposed to be controlled by the siding switches, partial local circuits at the ends of the block controlled by the relays, connections on the rolling equipment coöperating with the signal means, and means for completing the partial local circuits at the ends of the block through the signal controlling connections on the rolling equipment for operating the signal means. 95

2. The combination with a railroad block including siding switches, rolling equipment, signaling means on the rolling equipment, and electric circuit connections on said 100 rolling equipment for the signaling means, of high and low voltage relays at each end of the block, partial local circuits controlled by said relays, means for completing said partial local circuits through the circuit connections of the signaling means for operating the latter, a closed electric circuit including both relays at both ends of the block, resistances in said closed circuit, shunt circuits around said resistances, batteries in said shunt circuits, and spring-actuated circuit closers also included in said shunt circuits, said circuit closers disposed in position to be held normally open by the siding switches when the latter are closed. 115

3. The combination with a railway block 120 including siding switches, rolling equipment, a visual signal and brake controlling means on the rolling equipment, electrical devices for controlling the operation of said signal and brake controlling means, and circuit connections for said electrical devices, of long and short contact rails at the ends of the block, a shoe on the rolling equipment connected with the circuit connections on the latter and adapted to coöperate with 130

said contact rails, high and low voltage relays at both ends of the block, a closed circuit including the relays at both ends of the block, resistances included in said closed circuit, shunt circuits around said resistances, normally open circuit closers in said shunt circuits in position to be controlled by the siding switches, and partial local circuits at the ends of the block and controlled by said relays, each partial local circuit hav-

ing branches connected with the long and short contact rails.

In testimony whereof, I have signed this specification in the presence of two subscribing witnesses.

ANDREW J. ALLARD.
